(57) **CLAIM**

The ornamental design for a straw as shown and described.

DESCRIPTION

FIG. 1 is a rear, left, top perspective view of a straw showing my new design;

FIG. 2 is a front, right, bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is an enlarged top plan view thereof; and,

FIG. 8 is an enlarged bottom plan view thereof.

The broken lines in the drawings depict portions of the straw and form no part of the claimed design.

1 Claim, 8 Drawing Sheets
